UNITED STATES PATENT OFFICE.

CHARLES F. BAUER, OF McCONNELLSVILLE, OHIO, ASSIGNOR OF ONE-HALF TO GEORGE H. BAIN, OF McCONNELLSVILLE, OHIO.

INCUBATOR.

No. 799,514.

Specification of Letters Patent.

Patented Sept. 12, 1905.

Application filed September 15, 1904. Serial No. 224,529.

To all whom it may concern:

Be it known that I, CHARLES F. BAUER, a citizen of the United States, and a resident of Mc-
Connellsville, in the county of Morgan and
5 State of Ohio, have made a certain new and
useful Invention in Incubators; and I declare
the following to be a full, clear, and exact de-
scription of the same, such as will enable others
skilled in the art to which it appertains to make
10 and use the invention, reference being had to
the accompanying drawings, and to letters of
reference marked thereon, which form a part
of this specification.

Figure 1 is a perspective view of the upper
15 part of the invention. Fig. 2 is a perspective
view of the under part of the same. Fig.
3 is a longitudinal sectional view on line 3 3
of Fig. 1.

The invention relates to egg-trays for incu-
20 bators; and it consists in the novel construc-
tion and combinations of parts, as hereinafter
set forth.

In the accompanying drawings, illustrating
25 the invention, the letter *a* designates the frame
of the tray, which consists, mainly, of the side
bars *b* and the beveled transverse partition-
bars *c*, which are arranged in series at the
proper distance apart to provide a compart-
30 ment for the reception of an egg. These par-
titions *c* are designed to be placed on the up-
per and lower sides of the frame and have an
alternate arrangement, so that the basis of
the lower partition-bars (indicated at *d*) form
35 center bearings for the upper compartments,
and similarly when the tray is reversed the
basis of the upper partition-bars (indicated at
e) form the rests. In contact with these rests
or bars extends the bottom *d'*, which is made
40 of grit-gauze or other suitably frictional
cloth, said bottom being a strip sufficiently
wide to extend between the side bars of the
frame and sufficiently long to have its end
portions wound, more or less, on end rollers *f*,
45 which are provided with journals *g*, seated in
the ends of said side bars in open bearing-
slots *h* thereof. These rollers are exteriorly
inclosed by the end casings or boxings *k*, which
extend across the ends of the frame and are
50 provided with the upper flanges *m*, the lower
flanges *n*, and the side flanges *p*, which ex-
tend along the bearing-slots *h* to the journals
g and serve to hold them in position. These
end casings are secured to the side bars by

screws *s* and are easily removable in order to
permit the rollers and bottom cloth to be 55
taken out for cleaning or other purposes.
One journal of each roller is provided with a
key-seat, as at *t*, whereby it may be turned
by means of a suitable instrument for this
purpose. 60

Parallel to the side bars are the longitudi-
nal metal partitions *w*, which are placed apart
about the length of an egg and are designed
to prevent the eggs from traveling endwise
and coming in contact with each other when 65
turned by the motion of the bottom cloth.
These partition-plates are usually notched to
engage the transverse bars and brace them
securely in position.

The eggs are designed to be placed in the 70
compartments of the upper tray-section. Their
sides are adjacent to the beveled walls of the
transverse bars and their ends adjacent to the
longitudinal partition-plates *w*, while they rest
on the bottom cloth at the upturned center 75
bases of the lower partitions. All the eggs
of the upper tray-sections can be turned at the
same time and in either direction by turning
the proper roller at the end of the frame. To
turn them to the left, the right-hand roller is 80
moved, and for the reverse turning the left-
hand roller.

The upper tray-section, as shown, is de-
signed for hens' eggs, and its beveled parti-
tions are made somewhat thicker than those 85
of the lower tray-section, which is designed
to provide larger compartments for the larger
eggs of turkeys and ducks.

By the means herein shown the eggs can be
slowly turned without danger of collision 90
either endwise or sidewise.

By turning the tray over it can be used for
eggs of different sizes, and thus obviate the
necessity of having extra trays for this pur-
pose, and it has the further advantage in the 95
relation of preserving the even temperature
of the tray, the introduction of a cold tray
into the incubator being undesirable.

Having described the invention, what I
claim, and desire to secure by Letters Patent, 100
is—

1. An egg-compartment tray, for incuba-
tors, comprising a frame, a movable cloth
bottom for the compartments of the tray,
transverse beveled partition-bars above the 105
bottom, similar bars below the bottom, re-

movable adjusting-rollers for the cloth bottom, and removable end casings inclosing said rollers, substantially as specified.

2. An egg-compartment tray for incubators, comprising a frame, a movable cloth bottom for the compartments of the tray, end rollers for said bottom, upper compartment-partitions, above said cloth bottom, and lower compartment-partitions below said cloth bottom, and out of line with said upper compartment-partitions, substantially as specified.

3. An egg-compartment tray for incubators, having an upper tray-section, and a lower tray-section, a movable strip bottom, for the compartments of the tray located between the tray-sections and removable end rollers for said bottom, substantially as specified.

4. In an egg-compartment tray for incubators, the combination with the longitudinal bars, having open slot-bearings, of the beveled partition-bars, movable bottom strip, journaled end rollers, and removable flanged end casings, substantially as specified.

5. An egg-compartment tray for incubators, having beveled transverse partitions, me-

tallic longitudinal partitions, and removable end rollers, and a strip cloth bottom, mounted on said rollers, substantially as specified.

6. A reversible egg-compartment tray, for incubators, having a double set of transverse partition-bars, whereof the lower set form rests for the compartments between the bars of the upper set, substantially as specified.

7. In an egg-compartment tray, the combination with end slotted longitudinal side bars, and beveled transverse partition-bars, of journaled end rollers, and flanged removable end casings, substantially as specified.

8. An egg-tray for incubators having end rollers, a movable cloth bottom carried by said rollers, and a double series of partitions out of line with each other and located above and below said movable bottom, substantially as specified.

In testimony whereof I affix my signature in presence of two witnesses.

CHARLES F. BAUER.
